Fig. 7.

This technical drawing illustrates a mechanical assembly, likely a component of a larger machine. The assembly features a central vertical structure with a flared base. A horizontal beam or rod, labeled 117, is attached to the left side. A cylindrical component, labeled 115, is positioned near the base. A circular part, labeled 102, is attached to the lower left. A vertical rod, labeled 116, extends downwards from the main structure. Various other parts are labeled with numbers such as 118, 119, 121, 122, 123, 124, 125, 126, 127, 128, 129, 130, 131, 132, 133, and 134. The drawing uses solid lines for main parts and dashed lines for hidden features or reference points.

METHOD AND APPARATUS FOR MAKING SHADES

Joseph O. Howard, Chicago, Ill., assignor to Sail-Me Company, Inc., Chicago, Ill., a corporation of Illinois

Application November 22, 1935, Serial No. 51,141

10 Claims. (Cl. 93—1)

This invention relates to a method of and apparatus for manufacturing rotating lamp shades, or the like, from a hollow blank of paper, parchment, or other suitable material.

5 A principal object of the invention is the provision of a novel method of and apparatus for transforming a hollow blank by means of a cutting or stamping operation into two component parts, each of which is adapted for use in the 10 finished article, and one of which is at the same time cut to provide a plurality of separate, similar and adjacent portions comprising extensions of one end thereof.

Another important object of the invention is 15 the provision of the further step of and apparatus for forming said component part having the separate extension portions into the desired shape by directing the free ends of the latter toward a common point and securing them together in 20 that position by means of an eyelet or other similar fastening member.

A further important object of the invention is 25 the provision of the additional step of and apparatus for securing to said other component part an upstanding bearing member.

Another important object of the invention is 30 the provision of the further step of and apparatus for securing to said eyelet or retaining member a bearing member in such manner as to allow 35 for wide variations in size of said two members while insuring a satisfactory union thereof.

Numerous other objects and advantages of the 35 invention will be apparent as it is better understood from the following description, which, when taken in connection with the accompanying drawings, discloses a preferred embodiment thereof.

In the drawings,

Figure 1 is a front elevational view of a machine for performing the cutting operation;

40 Fig. 2 is an enlarged vertical section taken substantially on the line 2—2 of Fig. 1;

Fig. 3 is an enlarged vertical section taken substantially on the line 3—3 of Fig. 1;

45 Fig. 4 is an enlarged detail sectional view taken substantially on the line 4—4 of Fig. 3;

Fig. 5 is a side elevational view of a machine for performing the forming and fastening operation;

50 Fig. 6 is a front elevation of the machine of Fig. 5;

Fig. 7 is an enlarged detail side elevation, with parts in section, of a part of the machine of Fig. 5;

55 Fig. 8 is an enlarged detail elevational view

of a safety device forming a part of the machine of Fig. 5;

Fig. 9 is an enlarged vertical sectional view of the post employed in the machine of Fig. 5 comprising a retaining member and the male part of 5 the riveting die;

Fig. 10 is side elevation of a machine for joining the bearing member to the eyelet or retaining member;

Fig. 11 is an enlarged detail elevation of the 10 lower end of the riveting tool of the machine of Fig. 10;

Fig. 12 is a top plan view of a completed as- 15 semblage resulting from the operation of the ma- chine of Fig. 10, with parts broken away;

Fig. 13 is a vertical section taken substantially on the line 13—13 of Fig. 12;

Fig. 14 is an elevational view, partly in section, 20 of a machine for inserting the upstanding bearing member into the supporting part of the shade;

Fig. 15 is an elevational view of one form of 25 blank which may be used in conjunction with the instant method and apparatus;

Fig. 16 is an exploded elevation of the blank 30 of Fig. 15 after the cutting operation has been performed;

Fig. 17 is a vertical sectional view through the main part of the shade resulting from the blank of Fig. 15 after the separate extension portions have been secured together;

Fig. 18 is a view similar to Fig. 17 after the bearing member has been secured in place;

Fig. 19 is a detail top plan view of Fig. 18, with parts broken away; and

Fig. 20 is a vertical sectional view through a 35 portion of a completed shade comprising one of the articles which is adapted to be manufactured in accordance with the instant method and apparatus.

Referring more particularly to the drawings, reference numeral 31 indicates in general a machine adapted to perform the first operation of the instant method. The operation consists in cutting a hollow blank of paper, parchment, or the like, such as that indicated by reference numeral 32 in Fig. 15, so as to transform said blank into two component parts 33 and 34 (illustrated in Fig. 16).

The part 33 comprises the tip portion of the blank 32, and is adapted to be used as a supporting member for the main part 34 in a manner to be later described. In the cutting operation the severing of the tip portion 33 also determines the shape of the upper edge portion of the main part 34, so that no appreciable amount of material is 55

wasted. At the same time, the upper portion of the main part 34 is cut along a plurality of curved lines 35 to form a plurality of separate and adjacent portions 36, each of which comprises an extension of the main part 34. Adjacent its upper end, each of the extensions 36 is provided with a substantially centrally located aperture 37.

The above described cutting operation may be readily accomplished in a series of similar and successive steps by means of the machine 31 illustrated in Figs. 1 to 4, inclusive. In this machine, which is provided with a suitable base or standard 38, a substantially cone-shaped member or mandrel 39 is mounted in a suitable upstanding bracket 41, which is preferably formed integral with the base 38. A shaft portion 42 of the mandrel extends through the bracket 41 and is drawn into and held in place by suitable nut, or the like, 43.

A frustum-shaped collar 44 is rotatably mounted upon the shaft portion 42 on the inner side and adjacent the bracket 41, being spaced therefrom by a suitable washer 45. This collar 44 is provided with a plurality of equally spaced ratchet teeth 46 around that portion of its periphery adjacent the bracket 41. Adjacent its inner end, the collar 44 is provided with a plurality of radially extending apertures 47 which, when the collar 44 is properly positioned on the shaft 42, coincide with a plurality of similar radially disposed apertures 48 in the shaft 42. The inner ends of the apertures 48 communicate with an axial bore 49 in the shaft 42, which in turn is connected in any suitable manner to a suction hose 51 extending from a vacuum pump (not shown) of usual or well-known construction. The apertures 48 are in constant communication with the apertures 47 due to a circumferential channel 53 around the shaft 42.

The mandrel 39 is also provided with an elongated relief port 52 open to the atmosphere at each end, its inner end 53 terminating inwardly of and adjacent the inner end of the collar 44. The upper surface of the mandrel 39 is horizontally disposed, and has secured thereto, as by means of screws 54, a die plate 55 comprising the female part of a cutting die.

A steel rule die 56, comprising the male part of the cutting die, is mounted in any suitable manner on the lower end of a reciprocable shaft or ram 57. The ram 57 is mounted on the base or standard 38 by means of a bearing plate 58, and is reciprocated by the usual linkage 59, which is in turn actuated by the drive shaft 61 under the control of a clutch 62 shown in dotted lines in Fig. 2.

Rigidly secured to a part of the linkage 59 which actuates the ram 57, is a vertically disposed spring bar 63, the lower end of which is bent forwardly to provide a horizontally disposed tooth 64. As the bar 63 is reciprocated in conjunction with the ram 57, the tooth 64 in its upward movement engages a tooth 46 of the collar 44 and rotates the latter a predetermined distance in a counterclockwise direction, viewing Fig. 3.

The number of teeth 46 employed, is equivalent to the number of extensions 36 which it is desired to provide on the member 34. In the instant disclosure eight teeth are shown, so that upon each reciprocation of the indexing bar 63, the collar 44 is rotated one-eighth of a full revolution. It is to be understood, of course, that any other desired number of teeth 46 may be employed.

One complete cycle of the machine 31 consists of eight successive cutting movements of the ram 57, which includes the rotation of the collar 44

through one complete revolution. To insure the exact number of revolutions of the clutch 62 and shaft 61 by the driving member 65 for each operation of the machine, the following control mechanism is employed:

A control rod 66, preferably foot operated, extends through and is mounted for vertical reciprocal movement in the base 38. The upper end of the rod 66 cooperates with and is adapted to control the clutch 62 in the usual and well-known manner. Rigidly secured to the rod 66 adjacent its upper end, by means of a set screw 67, is a forwardly extending arm 68. A coil spring 69 is slidably mounted on the rod 66 between the arm 68 and the base or standard 38, which urges the arm 68 upwardly into contact with the periphery of a cam disk 71.

This cam disk 71 is rotatably mounted on a stud shaft 72, and is provided with a flattened portion 73 on its peripheral surface against which the upper surface of the free end of the arm 68 normally engages. Mounted on the shaft 72 adjacent the cam disk 71 and rigidly secured thereto is a gear wheel 74 having eight angular teeth. A disk 75, comprising a part of the clutch 62, has an actuating stud or pawl 76 secured thereto which is adapted to strike against a tooth of the gear wheel 74 to rotate the latter one-eighth of a revolution for each revolution of the shaft 61 and clutch 62.

The operation of the machine 31 above described is as follows: The hollow blank 32 is placed over the mandrel 39 with its inner surface adjacent its open end fitting closely over the inner portion of the collar 44, thereby loosely engaging the mandrel 39 and firmly engaging the collar 44.

The operator then pushes the control rod 66 downward, which performs two functions. First, by means of a suitable linkage 77, it opens a control valve 78 in the suction hose 51. Since this draws the air out of the bore 49 and the apertures or passages 48 and 47 communicating therewith, and since the bottom portion of the blank 32 closes the outer ends of the apertures 47, the blank is held firmly in place on the collar 44 by suction. Second, depression of the rod 66 causes engagement of the clutch 62 to allow the driving member 65 to reciprocate the ram 57, and also carries the arm 68 downward against the action of spring 69 out of the path of rotation of the circumferential surface of the cam disk 71.

During the first part of the initial rotation of the clutch mechanism 62, the actuating lug 76 strikes a tooth of the gear wheel 74 to rotate the cam disk 71 sufficiently to move the flattened portion 73 out of its lower horizontal position. Release of the rod 66 does not result in its return to clutch disengaging position under the influence of spring 69, therefore, since the upper surface of the arm 68 will engage the circumferential surface of the cam disk 71 to prevent return movement of rod 66.

The driving member 65 will continue to reciprocate the ram 57, therefore, and upon each revolution of the disk 75, which corresponds to a reciprocation of the ram 57, the cam disk 71 will be rotated one-eighth of a revolution. At the end of a complete revolution of the cam disk 71, that is, at the end of eight operations of the ram 57, the flattened portion 73 of the disk 71 will be returned to its lower horizontal position of Fig. 2, permitting the spring 69 to automatically return the rod 66 to its upper position to

disengage the clutch 62 and close the control valve 78 in the suction hose 51.

One complete operation of the machine 31 is thus automatically terminated, which constitutes eight successive reciprocations of the ram 57. On each upstroke of the ram 57, the indexing bar 63 rotates the collar 44 one-eighth of a revolution to present an uncut portion of the blank 32 to the cutting die 55, 56. Upon each cutting operation, that portion of the blank 32 which is cut is flattened out on the die plate 55. If this portion were returned to normal position by contact with the mandrel 39 as the blank 32 is rotated, the blank will have a plurality of longitudinal creases remaining at the end of the operation. The provision of the relief port 52 avoids this creasing, however, by keeping the major portion of the interior of the hollow blank open to the atmosphere.

The above described operation results in the formation of the two component parts 33 and 34, shown in Fig. 16, and the next step of the instant method is that of deflecting the separate extensions 36 of the part 34 into their desired positions and securing their free ends together. The result of this operation is illustrated in Fig. 17 where the extensions 36 are shown secured in their deflected positions by means of a rivet or eyelet 79 extending through the several apertures 37 which have been axially alined. In this position, the extensions 36 are bent over with one longitudinal edge higher than the other, which is a result of the particular curvature given the lines 35, to form a plurality of radially disposed vanes adjacent each other with spaces therebetween.

Referring to Figs. 5 to 9, inclusive, reference numeral 81 indicates in general a machine for deflecting the extensions 36, as above described, holding them in deflected position, and securing their free ends together by means of the eyelet 79. This machine comprises a standard 82 rigidly secured to or formed integral with a base 83 and a supporting member or bearing bracket 84 also secured to and upstanding from the base 83.

A frustum-shaped retaining member 85, upon which the main part 34 of Fig. 16 is adapted to be positioned, is rotatably mounted on a vertical tool post 86, which in turn is secured in any desired manner to and extends upwardly from the bracket 84. The member 85 is provided with a plurality of radial apertures or passages 87 which communicate at their inner ends with a bored recess 88 extending upwardly into the post 86 (Fig. 7). The recess 88 is connected in any desired manner by means of a control valve 89 mounted in the bracket 84 with a suitable vacuum or suction pump (not shown).

Slidably and non-rotatably mounted in the upper end of the post 86 is a vertically disposed tool 91 (Fig. 9). The upper end of the tool 91 is provided with a reduced portion 92 having a countersunk recess 93 in its end surface and a further reduced neck portion or circumferential groove 94 adjacent thereto. At the base of the reduced portion 92, the tool 91 is provided with an annular groove 95 having a rounded bottom and comprising the stationary part of a riveting die.

The upper end of the frustum-shaped member 85 terminates in a plurality of angular teeth 96, for a purpose to be later described. The lower end of the member 85 is provided with a ratchet gear 97 having eight teeth, with which a recip-

rocable pawl 98 is adapted to co-operate as an indexing mechanism for rotating the member 85 and the part 34 being operated upon. The number of teeth in the gear 97 depends upon the number of extensions 36 of the main part 34.

The indexing pawl 98 is connected by means of a lever 99 to a crank disk 101 rigidly secured to a shaft 102 which is rotatably mounted in the bracket 84 and another bracket 103 secured to the base 83. Mounted for horizontal sliding movement in the bearing bracket 103 is a supporting bracket 104 having a forwardly extending operating lever 105. An idler pulley 106 is rotatably mounted on the bracket 104, so that when it is pulled forward by the control lever 105, it tightens a belt 107 to drive a pulley 108 rigidly mounted on the shaft 102 from a pulley 109 secured to the main drive shaft 111. A hand operating crank 112 is also rigidly secured to the shaft 102.

A cam disk 113 is rigidly secured to the shaft 102 adjacent the crank disk 101, and is adapted to engage and co-operate with a curved surface 114 at the lower end of an arm 115 which is pivotally mounted on a stud shaft 116 supported by the bracket 84. The curved surface 114 is kept in engagement with the cam 113 by means of a spring 117 secured at one end to the lever 115 and at the other end to the standard 82 which urges the lever 115 in a counterclockwise direction viewing Figs. 5 and 7.

Rigidly secured at one end to the free end of, and forming part of, the lever 115 is a rod 118 extending at substantially ninety degrees to the main part of the lever 115. An axially disposed pilot or guide pin 119 is slidably mounted in the free end of the rod 118, and is spring urged to its outermost position, shown in full lines in Fig. 7. Detachably secured, at 121, to the rod 118 is an actuating bar 122 which terminates adjacent the end of the pilot 119 and has a substantially U-shaped deflector element 123 secured to its free end.

A ram or vertically reciprocable riveting member 124 is slidably mounted on the standard 82 by means of a bearing plate 125, and is connected at its upper end in any suitable manner to the usual operating mechanism, including a lever 126 pivoted at 127 to the standard 82 and at 128 to a link 129. The link 129 is pivotally connected to a crank disk 131 which comprises the driven part of a one-revolution clutch, the driving part of which is connected to the constantly rotating drive shaft 111, said clutch being under the control of a treadle rod 132.

An interlocking or safety device is provided for preventing operation of either the arm 115 or the ram 124 when the other is displaced from its normal or retracted position. This device comprises a horizontal, forwardly extending bar 133 which is rigidly secured to the clutch control rod 132, and a disk 134 which is secured to the shaft 102 and is provided with a flat portion 135 (Fig. 8). The flat portion 135 is normally in its horizontal position above the shaft 102, and the bar 133 is in its upper position directly above the disk 134, as shown in broken lines in Fig. 8, so that either the arm 115 or the ram 124 may be operated.

If the arm 115 is not in its retracted position, however, the flat portion 135 will not be in its position of Fig. 8, and the disk 134 will prevent downward movement of the bar 133. On the other hand, with the arm 115 in its normal retracted position, the bar 133 may be lowered by the control rod 132 to its full line position of Fig. 8 to initiate an operation of the riveting mechanism.

while at the same time blocking the rotation of disk 134 to prevent the operation of arm 115.

The crank disk or clutch member 131 is provided with an annular cam surface 136 against which the end of a crank arm 137 engages. The crank 137 is secured to or formed integral with a shaft 138 and is pivotally mounted at 139 in the standard 82, so that upon each revolution of the driven clutch member 131, the shaft 138 is rotated clockwise and then counterclockwise (viewed from its front end) through a small angle.

At its forward end, the shaft 138 is connected to an eyelet feeding mechanism or conveyer 141, which is pivotally mounted at 142 on the plate 15, 125, so that the above described rotation of the shaft will swing the feeding mechanism 141 about its pivot point 142. Thus, as the ram or riveting member 124 travels downward, it picks up a rivet or eyelet 79 from the lower end of the conveyer 20 141, and the latter is swung out of the path of movement of the ram; and when the ram returns to its upper position, the conveyer is swung back to normal position. At its upper end, the conveyer 141 is provided with the usual magazine 25 hopper 143.

The operation of the above described machine 30 81 is as follows: The cut part 34 is placed over the frustum-shaped member 85 and properly positioned thereon with the bottom portions of the extensions 36 coinciding with the base portions 30 of the teeth 96. Opening of the control valve 89 will cause a suction through the passage 88, 87 to hold the part 34 on the member 85.

The operator then pulls the lever 105 forward 35 which causes rotation of the shaft 102. Each rotation of the shaft 102, by means of the cam disk 113 and spring 117, moves the lever 115 from its full line position to its broken line position of Fig. 7 and back again. In its downward movement, the pilot 119 enters the aperture 37 in the associated extension 36 and the member 123 engages the upper end of said extension 36. Further movement of the arm 115 causes the pilot 119 to enter the recess 93 in the tool 40 91 and be telescoped into the rod 118, and the member 123 bends the extension 36 downward over the associated angular tooth 96 until the outer end of the aperture 37 engages the undercut shoulder on the tool 91 formed by the groove 45 94. The return movement of the arm 115 under the influence of the spring 117 therefore leaves the bent-over extension 36 in deflected position. In this operation, the angular tooth 96 insures a canting or twisting of the extension 36 for a 50 purpose to be later described.

Between each of the downward movements of the arm 115, the shaft 102 rotates the part 34 and members 85, 86 and 91 through one-eighth of a revolution to bring the next adjacent extension 36 in line with the members 119 and 123. This indexing movement is accomplished, as above described, by means of the crank 101, link 99 and pawl 98 actuating the ratchet gear 97. As soon as the last extension 36 has been 55 deflected and hooked over the reduced end portion 92 of the tool 91, the operator pushes the lever 105 back to normal position to stop the shaft 102. If the shaft is not stopped at the correct point, the disk 134 will aid in properly 60 positioning it in the manner of a balance weight, or the hand crank 112 may be employed.

The treadle rod 132 is then depressed to release the clutch 131 for one revolution. This causes the ram 124 to slide downwardly, pick 65 an eyelet 79 out of the conveyer 141 before the

latter is swung out of its path, force the eyelet through the apertures 37 impaled upon the reduced portion 92 of the tool 91, and rivet the several extensions together by compressing the lower edge of the eyelet into the annular groove 5 95 in the tool 91. The ram 124 then returns to its upper or inoperative position, the valve 89 is closed, and the part 34 removed from the member 85 to complete the operation.

The next step of the instant method comprises 10 the securing of a dome-shaped bearing member within and to the eyelet 79. In Figs. 12 and 13, this bearing member is indicated at 145 and is provided with a horizontal, circumferential flange 146 upon which the under surface of the 15 eyelet 79 rests. The bearing member 147 of Figs. 18 to 20, inclusive, is similar to the member 145 except that it is provided with a laterally extending counterweight 148 formed integral with the horizontal flange 149 which is otherwise the same 20 as the flange 146.

In Figs. 10 and 11 is shown a machine, indicated generally by reference numeral 151, for securing a bearing member 145 or 147 to the eyelet 79, which comprises a suitable base 152 upon which is mounted a standard 153 and a block 154. The upper part of the block 154 is or may be shaped to hold the specific article incorporating the eyelet 79, such as the main part 34 of the lamp shade shown in Fig. 17. Secured to or 30 formed integral with the upper surface of the block 154 is an upstanding stud 155 for properly centering the bearing member 145 or 147 which is placed thereon with its flange 146 or 149 resting on the horizontal surface of the block 154. 35 The part 34 or other article incorporating the eyelet 79 is then placed on the block 154 with the eyelet surrounding or in axial alignment with the bearing member.

A ram or riveting member 156 is mounted on 40 the standard 153 by means of a bearing plate 157 for vertical reciprocal movement. The upper end of the ram 156 is connected, by a link 158, to one end of a lever 159 which is pivotally mounted on the standard 153 intermediate its 45 ends at 161. The other end of the lever 159 is pivotally connected at 162 to one end of a rod 163, the other end of which is pivotally connected at 164 to a treadle 165 which is pivoted at 166. A spring 167 is secured to the pivot 162 50 at one end and to the standard 153 at its other end at 168. A suitable stop 169 is provided for limiting counterclockwise movement of the lever 159, and an adjustable stop 171 is mounted on the forward end of the lever 159 for limiting 55 clockwise movement thereof.

A riveting tool 172 is secured to or formed integral with the lower end of the ram 156, and terminates in a tapered portion 173 and an axially disposed, spring-urged pilot member 174. 60 At its lower end, the tapered portion 173 of the riveting tool is hollow-ground at spaced intervals around its surface, as shown at 175 in Fig. 11, to provide a plurality of circumferentially spaced prongs 176.

After the eyelet 79 or the member, such as the part 34, to which the eyelet is secured has been properly positioned relative to the bearing member 145 or 147, as explained above, the operator actuates the treadle 165 to lower the rim 70 156 and tool 172. The pilot 174 insures proper centering of the eyelet 79 if the latter is resting on top of the bearing member. After the pilot contacts the upper surface of the bearing member, further downward movement of the ram 75

156 results in a telescoping of the pilot upwardly into the tool 172. At the same time, the prongs 176 will partially shear away and displace a portion of the outer surface metal of the bearing member at a plurality of points around the circumference thereof, and press the same against the upper surface of the eyelet to form a plurality of spot rivet points 177. The stop 171 may be adjusted to limit the downward movement of the riveting tool to prevent a misshaping of the members being secured together.

With the above described method of securing the bearing member and eyelet together, it will be apparent that a satisfactory union therebetween will be assured, while permitting a wide variation between the relative sizes of the two parts. This is of particular importance from the angle of manufacturing costs, since standard eyelets may be employed, and the bearing members need not be held within very close limits.

The last and final step in the instant method is that of making a supporting member for the rotating part 34 of the lamp shade from the tip portion 33 (Fig. 16) of the original blank. To do this, a pin 178 (Fig. 20) is forced through the apex of the tip portion 33 and secured thereto in any desired manner, as by means of heat resisting cement 179.

In Fig. 14 is shown a device, indicated generally by reference numeral 181, for impaling the tip portion 33 on the pin 178. This device comprises a base 182 and an upstanding post 183 secured thereto or formed integral therewith. A cap or head member 184 is slidably mounted on the upper end of the post 183; relative movement of the two parts being limited by a set screw 185 extending through the wall of the cap 184 and engaging within a vertical groove 186 in the post 183. A coil spring 187 surrounds the post 183, with its ends abutting against the base 182 and the cap 184, respectively, to resiliently maintain the latter in its uppermost position.

The upper end of the cap or head member 184 is tapered or so shaped as to fit snugly within the tip portion 33, and is provided with an axially disposed passageway or bore 188. Upstanding from and secured to or formed integral with the upper end of the post 183 is a pin 189 which is of slightly smaller diameter than the bore 188, and the upper end of which normally extends for a short distance into said bore.

In using the device 181, the pin 178 is inserted in the bore 188 with its point or bearing end upward. The tip portion 33 is then placed over the cap 184 and, together with the cap, is depressed against the action of the spring 187. In this movement, the pin 178 remains stationary, so that the tip portion 33 is impaled thereon. Upon releasing the cap 184 it is moved back to normal position with the part 33 and pin 178 by the spring 187. The pin 178 is then rigidly secured to the tip portion 33 by inverting it, inserting a drop of cement 179 therein, and allowing the latter to harden.

In use, the tip portion 33 is mounted on a light bulb 191 (Fig. 20), and the part 34 is set thereon with the bearing member 141 co-operating with the pin 178 in the manner of a jewel bearing. When the bulb 191 is lighted, the rising warm air currents generated thereby will contact the extensions 36. Due to the particular shape given the extensions 36 in the cutting and forming operations, they constitute vane members against which the rising air currents will strike and between which said currents will flow up-

wardly. The main part 34 of the shade will therefore be rotated relative to the supporting tip portion 33 and light bulb 191.

To insure even and properly balanced rotation of the main part 34 of the shade, the counterweight 148 is so positioned as to compensate for any added weight on one side of the shade due to the overlapping of the material, as indicated at 192, in the formation of the cone 32.

The above described method may obviously be employed to make shades from hollow blanks having other shapes than that shown in the drawings, or articles of manufacture other than lamp shades.

It is thought that the invention and many of its attendant advantages will be understood from the foregoing description, and it will be apparent that various changes may be made in the steps and their order of accomplishment of the method described and in the form, construction and arrangement of the parts of the apparatus disclosed without departing from the spirit and scope of the invention or sacrificing all of its material advantages, the method and apparatus hereinbefore described being merely a preferred embodiment thereof.

I claim:

1. The method of making a rotating lamp shade, comprising severing a blank into a plurality of component parts, forming one of said parts into a rotatable element, and using another of said parts as a supporting member for said rotatable element.

2. The method of making a rotating lamp shade, comprising severing a hollow three-dimensional blank into a plurality of component parts, and using one of said parts as a rotatable element and another of said parts as a supporting member for said rotatable element.

3. The method of making a rotating lamp shade, comprising truncating a hollow cone-shaped blank, using the frustum as a rotatable element, and using the vertex portion as a supporting member for said rotatable element.

4. The method of making a rotating lamp shade, comprising severing a hollow three-dimensional blank into a plurality of component parts, and forming one end portion of one of said parts into a plurality of substantially radially extending vane members.

5. The method of making a rotating lamp shade, comprising severing a hollow three-dimensional blank into a plurality of component parts, forming one end portion of one of said parts into a plurality of substantially radially extending vane members, and securing the free ends of said vane members together.

6. The method of making a rotating lamp shade, comprising cutting a hollow three-dimensional blank into a plurality of component parts, cutting an end portion of one of said parts to form a plurality of separate adjacent members comprising extensions of said part, and forming said extensions into substantially radially extending vane members.

7. The method of making a rotating lamp shade, comprising cutting a hollow three-dimensional blank into a plurality of component parts, cutting an end portion of one of said parts to form a plurality of separate adjacent members comprising extensions of said part, bending said extensions inwardly toward the axis of said part, and securing the free ends of said extensions together.

8. The method of making a rotating lamp

shade, comprising cutting a hollow three-dimensional blank into a plurality of component parts, and in the same operation cutting an end portion of one of said parts to form a plurality of separate adjacent members comprising extensions of said part.

9. The method of making a hollow rotatable member, comprising forming an end portion of a hollow three-dimensional blank into substantially 10 radially extending vane members, securing the hub portions of said vane members together by means of a retaining member, and permanently securing a bearing member to said retaining member.

10. The method of securing a hollow member having one closed end and a flange formed integrally therewith adjacent its open end to and within a hollow, open-ended member having an inner diameter which is less than the diameter 5 of said flange, comprising placing said first member within said second member, and partially severing and displacing a portion of said first member adjacent the closed end thereof and forcing said portion into firm contact with said 10 second member to maintain said second member in contact with said flange.

JOSEPH O. HOWARD.
